UNITED STATES PATENT OFFICE.

HARRY LANDSIEDEL, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

ADDING AND RECORDING MACHINE.

1,209,859.

Specification of Letters Patent. Patented Dec. 26, 1916.

Application filed November 12, 1912. Serial No. 730,888.

To all whom it may concern:

Be it known that I, HARRY LANDSIEDEL, a citizen of the United States, residing at the city of Poplar Bluff, county of Butler, 5 and State of Missouri, have invented a new and useful Adding and Recording Machine, of which the following is a specification.

This invention relates to adding and recording machines of that type which include a series of type-carriers mounted in lateral alinement, a series of stops selectively settable to limit movement of the type-carriers, and a series of keys each of 10 which is capable of successive operations 15 for the purpose of setting one or more stops to limit movement of any desired number of type-carriers.

One type of machine to which my present invention is particularly well adapted is described and illustrated in Hopkins's patent, 20 Number 1,039,130, issued September 24, 1912. In the accompanying drawings I have illustrated my invention embodied in and combined with an adding and recording machine constructed in accordance 25 with the adding and recording mechanism described and illustrated in the said Hopkins patent. I have shown my invention embodied in and combined with such 30 a machine for the purposes of convenience only, and it will be apparent to those skilled in the art to which the invention relates, that the entire invention, or essential parts thereof, are equally as well 35 adapted for use in other machines. The adding and recording machine of the said patent is well known commercially as the "Dalton" adding machine.

One object of the present invention is to 40 produce an improved arrangement of stops to limit the movement of the type-carriers in their excursions, so as to dispense with the necessity of a movable carriage for setting the stops, without increasing the number 45 of the numeral keys which correspond to the numerical alphabet, there being one key for each of the ten numeral figures.

Another object is to provide mechanism for restoring the stops to idle position be-

fore operation of the recording mechanism, 50 at the will of the operator, so that when error is made in striking the keys such error may be corrected and will not be entered in the added and listed items.

With these and other objects in view I 55 have illustrated one form of my invention in the accompanying drawings in which—

Figure 1 is a longitudinal sectional view of a machine embodying my invention. Fig. 2 is a horizontal sectional view above 60 the keys and key levers and stop mechanism, and below the type-carriers and adding mechanism. Fig. 3 is a perspective view of the stop setting devices, and the ends of the key levers by which the stops are selected. Fig. 4 is a sectional view illustrating the construction and arrangement of the stop selecting and setting devices. Fig. 5 is a perspective view of a portion of the mechanism controlling the stop selecting 65 and setting devices. Fig. 6 is a detail view of the connections from the total key and the devices for preventing operation of the total key at any time when carrying is incomplete. Fig. 7 is a view showing the 70 position of certain of the parts when the total key is operated. Fig. 8 illustrates one of the total wheel actuating racks in its forward position when taking a total.

The "Dalton" adding machine as at present on the market, and as described in the Hopkins Patent Number 1,039,130, includes ten numeral keys 1 arranged in rows in a key-board and mounted upon levers 2 extending toward the rear of the machine and 80 being pivoted upon a shaft 3. The rear or inner ends of the key levers terminate in projections or hammers 4, arranged in a row the plane of which is transverse to the planes of the rows in which the keys are 85 arranged. The said machine also includes a series of type-carriers 5 arranged in transverse alinement and pivotally supported upon a shaft 6. For each of said type-carriers there is a rack 7, which racks are 90 suspended from the shaft 6.

A main shaft 8 controls the type-carriers and racks in their parallel movements, and

operation of said shaft 8 is necessary before said type-carriers and racks may be operated to list or add numbers. This control is effected through a connection from the shaft 5 8 which includes a link 9, an arm 10 to which said link is pivoted, an arm 11 at each side of the series of type-carriers and racks and one of which is connected to the arm 10 by a pin and slot connection 12, and a 10 rod 13 carried by the lower ends of the arms 11 in front of the vertical extensions of the type-carriers and racks. Forward rocking of the shaft 8, through the connections described, swings forwardly the rod 13, thereby 15 permitting forward movement of the type-carriers and racks, such forward movement being effected by springs 14 connected to rearward extensions of the type-carriers (Fig. 1). The type-carriers have series of 20 type 15 on their forward ends, said type being movably mounted and having their printing faces within the arcs of the arcuate type-carriers. A platen or paper support 16 is mounted within the arcs of the 25 type-carriers and is arranged to support the paper upon which the records are made by operation of the type. A type-driving hammer 17 is provided for each type-carrier, said hammers being pivotally mounted upon a 30 supporting rod 18 and being actuated to drive the type in printing operations by means of springs 19. The hammers are normally held in idle position away from the type by latches 20. Forward movement of the type- 35 carriers automatically effects the release of the corresponding hammer by rubbing against a lever 21 and raising the forward end of said lever, thereby raising a corresponding bar 22 which is connected to the 40 corresponding latch 20. The shaft 18 is a rock shaft and supports a bail 23 which is automatically operated on the forward movement of the type-carriers, and said bail at the proper time engages the ends of the 45 bars 22 which are raised by operation of the corresponding levers 21, thereby pushing said raised bars 22 forwardly and effecting the release of the latches 20 from the hammers 17 which correspond to the type- 50 carriers which move to recording position. The bail passes above the bars 22 which are not raised by type-carriers moving to recording position so does not release any hammers except the hammers corresponding 55 to the type-carriers which move to record. The arrangement and operation of these recording devices is such that the type become perfectly alined in printing position adjacent to the paper support 16 before the 60 hammers are released, so that when the hammers strike the type the type will be driven to produce a clear and distinct impression.

The "Dalton" machine, and the machine of the Hopkins patent aforesaid, also in-

cludes a swinging frame 24, having cam 65 slots 25 in the upper ends of the sides of said frame. A rod 26 is supported in the slots 25 and a series of adding wheels 27 are revolvably mounted upon said rod. There is one wheel 27 for each actuating rack 7, and 70 said machine includes provisions for operating the frame 24 to lower the wheels 27 out of mesh with the racks 7 before said racks start on their forward excursions, and raise said wheels into mesh with said racks before said 75 racks start on their return excursions. By co-operation with suitable alining or carrying pawls 28 adding is effected, including carrying or transferring from lower to higher orders in the process of addition. 80 These elements and the means for effecting their operation are not included in my invention and I have not illustrated them in detail. It is in combination with these known and existing structures that my invention is 85 used, and having thus described the known and existing structure I will now proceed to describe my invention and its relation thereto.

At the rear of the machine is a series 90 of supporting posts 29. Two of said posts support a plate 30 and said plate 30 is connected to the remaining two posts by rods 31. A plate 32 is supported by the rods 31, and said plate has a series of parallel guide 95 ways 33 within which the depending heels 34 operate. The heels 34 are supported by the racks 7 by pin and slot connections 35 and are actuated downwardly by springs 36 connecting said heels with projections 100 of said racks, respectively. The heels 34 move within the guide ways 33 during the forward and backward excursions of the racks, and prevent lateral movement or oscillation of said racks. The under side of 105 the plate 32 is provided with a series of parallel passages or guide ways 37. There are nine of the passages 37, one for each numerical character or digit except for the digit "9," the front rod 31 constituting a 110 stop for the 9's and dispensing with the necessity of any guide way or passage 37 for the 9 stops. A plate 38 is supported by the rods 31 at the side of the plate 32 opposite from the plate 30. A series of 115 spiral elements 39 are revolvably supported by the plates 30 and 38, there being one of said spiral elements for each of the transverse passages or guide ways 37. The spiral element at the rear extends through an enlarged opening in the plate 30 and at its extending end is journaled in a bracket 40. The adjacent spiral element is also extended beyond the plate 30, but is not provided with any spiral portion on its extended 120 part. The extended part of the adjacent element 39 is also journaled in the bracket 40 and said extensions are provided with 125

intermeshing pinions 41. The remaining spiral elements are provided with intermeshing pinions 42 so that all of said elements will be rotated together. The spirals 5 of the adjacent elements 39 are oppositely arranged, because their rotation is in opposite directions, and it is necessary that they feed the stops hereinafter described in the same direction when rotated.

10 The upper ends of two of the posts 29 support a rock shaft 43 having arm 44 attached to its rear end and a longer arm 45 attached to its front end and terminating immediately over the extension or hammer 15 4 for the "9" key, so that when the 9 key is operated the arm 45 will be raised and the shaft 43 will be rocked. A series of nine arcuate arms 46 are loosely mounted upon shaft 43, the lower ends of said arms 20 terminating above the extensions or hammers 4 on all of the key levers except the lever for the "9" key upon which the arm 45 rests as above explained. A rod 47 is supported by the arms 44 and 45 above the 25 lower extensions of the arcuate members 46, so that when any numeral key lever is operated the corresponding element 46 will be rocked, thereby raising the rod 47 and rocking the shaft 43. The arcuate elements 46 30 extend above the plate 38 and are formed with downwardly extending tongues 48 which terminate a slight distance above the upper edges or surfaces of the spiral elements 39 and adjacent to the right side of 35 the guide plate 32. Springs 49, (Fig. 4) are connected to the members 46 and actuate said members downwardly, thereby restoring said members and the corresponding key levers and keys to idle position after 40 each operation.

The spirals on the elements 39 are spaced the same distance apart as are the passages 33, so that irrespective of the number of complete or partial revolutions imparted to 45 said elements the spiral portions thereof are always between the passages 33 and the grooves or passages formed by said spiral portions are always immediately below the passage 33.

50 The plate 38 supports a series of tubular magazines 50, in the present instance there being one of said magazines for each of the spiral elements 39. For convenience of illustration and operation I have illustrated 55 the magazines 50 arranged obliquely, projecting through the plate 38 and arranged to discharge into the groove or channel formed by the spirals on the elements 39. Each magazine contains a series of spherical stops 51 which, in idle position, are supported by the lowermost one of said stops resting upon the spiral element 39 at the right of the depending tongue 48 (Fig. 2). In each magazine there is one stop for each

type-carrier and rack, being nine type- 65 carriers and nine racks in the present instance, and, therefore, nine stops. These stops are fed transversely by the spiral elements 39 incidentally to the operation of the numeral keys. In being thus fed trans- 70 versely the stops are supported by the spiral elements and extend into the transverse passages or guide ways 37, and are thereby prevented from displacement. The pas- 75 sages 37 intersect the passages 33 (Figs. 6, 7 and 8), so that when the stops are fed transversely they pass across the passages 33, extending into said passages and constituting stops for the heels 34 in the forward excursion of the type-carriers 5 and 80 the racks 7.

An arm 52 (Figs. 1 and 4) is rigid with the rock shaft 43 and supports one end of the link 53 the opposite end of said link being connected to a depending portion of an 85 escapement dog or pawl 54. The said dog or pawl 54 is rigid upon a rod or shaft 55 removably supported between two of the posts 29 by means of pivot bearings 56 (Fig. 3). Another escapement dog or pawl 57 is 90 pivotally supported by the rod or shaft 55, and said two pawls are formed so that their edges adjacent to their upper ends abut together (Fig. 5). The movable pawl 57 is connected to the pawl 54 which is rigid on 95 the shaft 55 by a spring 58, the tendency of said spring being to draw said pawls into contact with each other. The pawl 57 projects a slight distance above the upper end of the pawl 54 for purposes which will here- 100 inafter appear.

The plate 30 has a depending portion which constitutes a bearing for one end of an escapement shaft 59. An escapement pinion 60 which, in the present instance, 105 is in the form of a ratchet wheel, is revolv- 110 bly mounted upon the escapement shaft 59 and is normally engaged by the dog or pawl 54, as clearly illustrated in Figs. 3 and 5. The outer surface of each of the teeth on the escapement pinion 60 is in the form of an entering oblique plane 61 (Figs. 3 and 5). Since the dog or pawl 57 is slightly longer than the dog or pawl 54, it follows 115 that when the escapement pinion 60 engages the pawl 54 the inner edge of the pawl 57 presses against the outer edge of the tooth of said pinion 60 which is in engagement with said pawl 54, as illustrated in Fig. 5. When the shaft 55 is rocked so as to move 120 the pawl 54 inwardly the spring 58 acts to draw the pawl 57 close against the edge of the tooth of the pinion 60 from which the pawl 54 is released. This permits the pinion 60 to be rotated, and as said pinion 125 rotates the pawl 57 is drawn inwardly under the tooth of said pinion following the tooth released by the pawl 54, the

said pawl 57 pressing inwardly along the oblique plane surface or cut away portion 61. This action places the upper end of the pawl 57 in the path of movement of the following tooth on the pinion 60 thereby stopping rotation of said pinion 60. Backward rocking of the shaft 55 will cause the pawl 54 to press the pawl 57 from under the tooth of the pinion 60 with which said pawl 57 has become engaged, and will move the said pawl 54 under said tooth, this operation being effected because the pawl 54 is somewhat shorter than the pawl 57. Since the escapement shaft 55 is connected with the rock shaft 43, and since the rock shaft 43 is rocked at each operation of a numeral key, it is obvious that the escapement is operated on the depression of each numeral key. The parts of the escapement as well as the rock shaft 43 and the connections thereof to the escapement are returned to their normal or idle positions after each operation of a numeral key by a spring 62 (Fig. 4) connecting the rod 47 with the link 53.

A plate 63 is attached to the shaft 59 and carries a pawl 64 engaging with the teeth of a ratchet pinion 65 which is integral with the pinion 60. A pinion 66 rigid upon the shaft 59 meshes with an actuating rack 67 loosely supported upon a shaft 68 (Figs. 1 and 3). A spring 69 is connected with the rack 67 and actuates said rack to rotate the shaft 59 at each operation of a numeral key, such rotation being permitted by the step by step movement of the escapement mechanism hereinbefore described. The shaft 59 also supports a pinion 70 which is in mesh with one of the pinions 42, so that whenever the escapement is operated by operation of any one of the numeral keys all of the spiral elements 39 will be rotated effectively to feed from right to left, that is from lower to higher orders, any of the stops 51 which had passed beyond the retaining gates or tongues 48. These elements are arranged in such relation to each other that the stops will be moved at each depression of a numeral key a distance equal to the distance between the guide passages 33 into which the stops extend so as to limit movement of the type-carriers and the racks in their forward movements.

The elongated spiral element at the rear supports a series of spherical stops 71, in addition to the stops 51 normally contained in the magazine 50 to be delivered upon said spiral element. The stops 71 extend into the passages 33 and will be engaged by the heels 34 and prevent movement of the several racks 7 prior to operation of numeral keys. As the numeral keys are operated the stops 71 are moved or fed laterally on to the extended portion of the rearmost spiral element 39, thereby moving said stops 71 from

lower to higher orders incidentally to the 65 operation of the keys and incidentally to the selecting and positioning of stops 51 upon and by the several spiral elements 39.

Since operation of the numeral keys results in operation of the spiral elements 39 to select and position the stops 51, and to move the stops 71, from lower to higher orders, it follows that reverse rotation of the spiral elements 39 will restore the stops 51 into the magazines 50, and will also restore the stops 71 in their normal or idle positions to prevent movement of all of the racks 7. This reverse operation of the spiral elements to restore the stops 51 into the magazines 50, and to restore the stops 71 in the path of movement of the heels 34, is accomplished automatically and incidentally to the listing or adding of a number. The rock shaft 8 supports an arm 72 (Fig. 1) upon which is pivoted a hook 73. The arm 71 and the hook 73 are swung forwardly at each operation of the rock shaft 8. An arm 74 is supported by a shaft 75 and is connected by means of a link 76 with an arm 77 upon the shaft 68. The rack 67 has a projection 78 adapted to be engaged by the arm 77 when said arm 77 is moved rearwardly, which operation will restore the rack 67 to its idle position thereby rotating the shaft 59 and operating all of the spiral elements 39 in a direction which is the reverse of their operation by the numeral keys. This reverse operation moves all of the stops 51 under the beveled lower ends 79 (Fig. 4) of the tongues or gates 48 and into their respective magazines 50, and also moves the stops 71 back to their normal or idle positions in which they extend into the passages 33 to prevent movement of all of the racks 7 until after the numeral keys have again been operated. When the shaft 8 reaches the forward limit of its movement, after the number represented by the type-carriers has been recorded, said shaft 8 is returned to its initial position by springs 80 (Fig. 2). At the limit of its forward movement the hook 73 engages an extension 81 (Figs. 1 and 2) thereby drawing with it the arm 74 which, through the link 76 and the arm 77, operates the rack 67, resulting in rotation of the spiral elements 39 effectively to move the stops 51 into their respective magazines and the stops 71 into their normal or idle positions. As the hook 73 reaches its idle position an arm thereof engages with a projection 82 thereby disengaging the hook 73 from the projection 81, and permitting the connections from the shaft 75 to the shaft 68 to be restored to idle position. A spring 83 suitably connected to one of the elements connecting the shaft 75 with the shaft 68 restores said elements to idle position after release of the hook 73. It will be noted that, as in the Hopkins patent, Num-

ber 1,039,130, and in the Dalton adding machine, the springs 80, in restoring the shaft 8 to idle position, also actuate the connections from said shaft effectively to cause the 5 rod 13 to restore the type-carriers 5 and the racks 7 to their rear or idle positions, causing the racks 7 to operate the adding wheels 27 to add the numbers recorded and to transfer from lower to higher orders in the 10 process of addition. The said connections also restore the hammers 17 into engagement with their respective latches 20.

Return of the stops 51 into their respective magazines 50 may be prevented at the 15 will of the operator, so that any number set up or represented by said stops may be repeatedly recorded or added without repeated setting of the stops. The mechanism for enabling the operator thus to repeat a number 20 comprises a device for preventing engagement of the hook 73 with the projection 81, so that said hook may move back and forth without operating the stop return devices. This repeat mechanism includes a 25 key 84 mounted in or adjacent to the rows of keys 1 and having the lower end of its stem pivoted to a lever 85 which is operatively mounted on a support 86. The rear or inner end of the lever 85 has pin-and-slot connection with a bell-crank device 87 which is pivoted to a support 88, and one end of which extends substantially vertically at the side of the arm 74 which supports the projection 81. The upper end of 30 the vertical arm of the bell-crank device 87 is provided with a laterally extending shield or flange 89 adapted to be operated under the projection 81 and constitute a surface against which the hook 73 may rub 35 when said hook is operated forwardly in listing or adding a number, as previously described. When the shield or flange 89 is positioned under the projection 81 engagement of the hook 73 with said projection 40 will be prevented, so that the number set up or represented by the stops 51 may be recorded or added as many times as desired without returning said stops to idle position. A spring 90 (Fig. 1) is effective to hold the 45 key 84 in its elevated position, and to hold the shield or flange 89 normally away from the projection 81, so that depression of the repeat key 84 is necessary in order to prevent engagement of the hook 73 with the projection 81 and permit the number to be 50 repeatedly recorded or added.

On some occasions error may be made in striking the numeral keys, thereby resulting in selecting and setting the wrong stop 51, which would result in an error in the item 55 listed and added unless corrected. For restoring the stops to idle position independently of operation of the type-carriers and racks I utilize a train of connections where-

by the spiral elements 39 may be manually 65 rotated in a direction which will restore the stops 51 into their respective magazines and will also move the stops 71 to normal position in which they will prevent operation of the racks and type-carriers. A correction key 91 has a stem extending through the key-board in or adjacent to the rows of numeral keys 1, and operating in a slotted guide 92 which is encircled by a spring 93. The spring 93 normally holds 70 the key 91 in its elevated adjustment but permits manual depression of said key. The stem of the key 91 is provided with a slot 94 which receives a pin 95 carried by an arm 96 whose front end is pivotally supported at 97. By this means operation of the key 91 will oscillate the arm 96. The rear or inner end of the arm 96 is pivotally connected to a link 98 the upper end of which is pivoted to an arm 99 attached to 80 the shaft 75. The shaft 75 is a rock shaft and has a pin 100 engaging behind a shoulder 101 on the hub of the arm 74, thereby permitting the arm 74 to be operated by the hook 73 without moving or disturbing the 85 shaft 75. However, downward movement of the arm 99 will rock the shaft 75 in a direction to cause the pin 100 to swing the arm 74 and the connections from said arm 74 rearwardly, causing the arm 77 to engage 90 the projection 78 and thereby restore the rack 67 to idle position, resulting in operation of the spiral elements 39 effectively to restore all of the stops, which had been operated, to their idle positions within their 95 respective magazines. Upon release of the key 91 the spring 93 expands to raise said key and restore the connections from said key to the shaft 75 to their idle positions, and permitting the spring 83 to restore the 100 connections from the shaft 75 to the shaft 68 to their idle positions.

In order to print the total contained or represented in the adding wheels 27, and to operate the type-carriers 5 and the racks 110 7 in connection with said adding wheels in clearing operations, it is necessary that said parts be permitted to operate without restraint by the stops 71. A key 102 has a stem extending through the key-board plate 115 and pivoted at its lower end to a lever 103 mounted upon a support 104. The rear or inner arm of the lever 103 is pivotally connected with one arm of a bell-crank lever 105, another arm of lever 105 is pivoted to 120 a link 106. The rear end of the link 106 is connected to a lever 107 the upper end of which is pivoted to an arm 108, which is attached to a rock shaft 109 (Figs. 1 and 6). Two arms 110 attached to the rock shaft 109 125 extend forwardly and support a rod 111 under rearward extensions of the movable heels 34 which are carried by the racks 7.

Elevation of the rod 111 will engage the rearward extensions of the heels 34 and raise said heels above the stops 71 and permit movement of the racks 7 in clearing operations. Depression of the key 102 will operate the connections above described effectively to raise the rod 111 and permit operation of the racks 7 and the type-carriers in total printing and clearing operations, although such operation is prevented prior to the completion of carrying or transferring, in the process of addition, so that one forward and backward movement of the rock shaft 8 is necessary after the listing of any one or more items before the total key may be depressed.

One of the posts 29 supports a pivoted cam 112. The plate 63 has a pin 113 (Fig. 6) which, in idle position, presses upon an arm of the cam 112 and holds said cam rearwardly against an abutment 114. When any numeral key is depressed the pin 113 is raised by the rotation of the escapement shaft 55, thereby removing said pin 113 from the arm of the cam 112. One side of the swinging frame 24 supports a pivoted arm 115 having a pin 116 extending over the upper edge of the cam 112. A bell-crank lever 117 is pivoted at the side of the cam 112 and said cam and said lever are actuated toward each other by a connecting spring 118. In idle position the pin 116 is engaged behind the upper arm of the bell-crank 117, thereby holding said arm forwardly, and the pin 113 is engaged upon the arm of the cam 112, thereby holding said cam rearwardly, thus extending and tensioning the spring 118 connecting said cam and said lever.

When the numeral key is operated the shaft 55 rotates and raises the pin 113 permitting retraction of the spring 118 and permitting forward movement of the upper portion of the cam 112, moving the shoulder of said cam under the pin 116 and raising said pin above the upper end of the lever 117. This permits the spring 118 to move the upper end of the lever 117 under the pin 116, movement of said lever 117 being limited by an extension 119 thereof engaging with a stud 120 upon the link 116. Thus the lever 117 is positioned to constitute an abutment for the link 106 and prevent operation of the total recording and clearing mechanism during the time that any of the stops 51 are in position upon the selecting and positioning devices 39. As previously explained the frame 24 is swung backward and forward during the listing and adding of numbers. When said frame is swung rearwardly to draw downwardly the adding wheels 27 previous to the forward movement of the type-carriers and racks in adding and listing operation, the pin 116 rubs

along the upper edge of the cam 112. Just previous to starting of the type-carriers and racks, on their return, the frame 24 is swung forwardly by suitable devices (not shown) and the pin 116 moves forwardly along the upper edge of the cam 112 and also along the upper edge of the lever 117, but does not engage behind the upper end of said lever 117, thereby leaving said lever in position to constitute an abutment to prevent operation of the link 106 and its connected parts. Assuming that the escapement shaft 55 has been operated to actuate the selecting and setting devices 39 to restore the stops 51 into their respective magazines, it is apparent that the pin 113 engages the projections of the cam 112 and restores said cam to idle position, leaving the pin 116 resting upon the upper end of the lever 117. Another operation of the frame 24 will move the pin 116 rearwardly beyond the upper end of the lever 117, and said pin 116 will drop behind the upper end of said lever 117. Forward movement of the frame 24 will then cause the pin 116 to engage behind the upper end of the lever 117 and draw the same forwardly in opposition to the spring 118, thereby moving the front end of the lever 117 below the stud 120, leaving the total printing and clearing mechanisms free for operation at the will of the operator. On this blank or idle stroke operation of the racks 7 and the type-carriers 5 is prevented by engagement of the sliding heels 34 with the stops 71. The operation of the machine in clearing operations is substantially the same as in the machine of the Hopkins patent and in the Dalton adding machine.

In the machine of the Hopkins patent and in the Dalton adding machine, there is a series of stops for each type-carrier, and a movable carriage whose operation is necessary for the purpose of positioning said stops. My present invention not only dispenses with the use of the movable carriage, but includes novel selecting and setting mechanism whereby the ten numeral keys may be utilized for setting a field of stops, in any desired relation, to represent the numbers to be listed and added. My present invention includes a series of stops, and ten numeral keys whereby said stops may be set without the use of any intermediate stop setting carriage.

While I have shown and described one preferred form and embodiment of my invention, it is apparent that there may be various changes and alterations in the construction and arrangement of the various parts without departure from the spirit and scope of my invention, and I do not restrict myself to the identical construction and arrangement shown and described.

What I claim and desire to secure by Letters Patent is:

1. In an adding machine, a series of stops, mechanism for selecting and positioning said stops, a device for actuating said mechanism, keys determining when said actuating device may operate, and a series of magazines arranged to receive said stops and to contain said stops in their idle positions.
2. In an adding machine, a series of movable stops, stationary supports for said stops, and means for selecting and moving from said supports certain of said stops while the remaining stops remain in idle position on said supports.
3. In an adding machine, a series of laterally movable stops, stationary supports for said stops, and mechanism for selecting and moving laterally from said supports selected ones of said stops while the remaining stops remain in idle position on said supports.
4. In an adding machine, series of laterally movable stops adapted to be positioned to represent numbers, stationary supports for said stops, a rotary positioning device for each series of stops, and mechanism for operating said positioning device effectively to move said stops from said supports and to position said stops to represent numbers.
5. In an adding machine, series of laterally movable stops, a rotary positioning device for each series of stops, and mechanism for operating said positioning devices to position said stops to represent numbers.
6. In an adding machine, series of laterally movable stops, a rotary positioning device for each series of stops, and means for selectively operating said positioning devices to position said stops to represent numbers.
7. In an adding machine, series of laterally movable stops, a support for said stops from which said stops may be moved to represent numbers, a positioning device for each series of stops, and means for operating said positioning devices to remove said stops selectively from said supports and to set said stops to represent numbers.
8. In an adding machine, series of movable stops, a positioning device for each series of stops, mechanism for operating said positioning devices to position said stops to represent numbers, and mechanism for operating said positioning devices to restore said stops to idle position, substantially as specified.
9. In an adding machine, series of movable stops, a magazine for holding each series of stops in idle position, a positioning device for each series of stops, means for operating said positioning devices to move said stops selectively from said magazines and to set said stops to represent numbers, and means for causing said positioning de-
10. In an adding machine, a support, a plurality of stops in said support, an element holding said stops in said support, an actuator for moving said stops to selected positions, means for moving said element to release said stops one at a time and to place the released stops under control of said actuator, means for operating said actuator to move said stops in one direction to selected positions, and a manipulative device for operating said actuator to move said stops in the opposite direction to place them again in said support.
11. In an adding machine, series of movable stops, a rotary positioning device for each series of stops, means for operating said positioning devices to position said stops to represent numbers, and means for restoring said stops to idle position.
12. In an adding machine, a series of magazines, a series of stops contained in each magazine, and means for removing said stops from said magazines and positioning stops so removed to represent numbers.
13. In an adding machine, a series of magazines, a series of stops in each magazine, means for selecting and removing said stops from said magazines and positioning said stops to represent numbers, and means for replacing said stops within said magazines.
14. In an adding machine, series of stops including stops for each of several digits, means for supporting the stops corresponding to each digit separate from stops corresponding to the other digits, mechanism for selecting and removing said stops from their supports and positioning said stops to represent numbers, movable elements whose movement is limited by said stops which are positioned as aforesaid, mechanism for operating said selecting and removing means to return said stops to idle position incidentally to the operation of said movable elements, and means for preventing said stops from being returned to their idle positions as aforesaid at the will of the operator.
15. In an adding machine, the combination with a number of elements corresponding respectively to each of several digits and an actuator for operating said elements simultaneously, of a series of parts adapted to be positioned to represent the digits of numbers, and optional means for placing said parts under control of said elements whereby said parts will be positioned by the operation of said elements to represent the digits of numbers.
16. In an adding machine, the combination of elements corresponding respectively to each of several digits, a series of parts adapted to be positioned to represent num-

bers, means for supporting said parts out of control of said elements, means for placing said parts selectively under control of said elements, and an actuator for operating said 5 elements to move the parts controlled thereby to position to represent numbers.

17. In an adding machine, the combination of elements corresponding respectively to each of several digits, a series of parts 10 adapted to be positioned to represent numbers, means for supporting said parts out of control of said elements, means for selectively placing said parts under control of said elements, an actuator for operating said 15 elements to move said parts to position to represent numbers, and means for actuating said elements to move said parts to their starting points.

18. In an adding machine, the combination 20 of elements corresponding respectively to each of several digits, a series of parts adapted to be positioned to represent numbers, a support for supporting said parts out of control of said elements, means for 25 placing said parts selectively under control of said elements, an actuator for operating said elements as an incident to the placing of said parts under control thereof, automatic means for actuating said elements to 30 restore said parts to their starting points, and optionally operable means for actuating said elements to restore said parts to their starting points.

19. In an adding machine, the combination 35 with a series of reciprocating elements, and means for actuating said reciprocating elements in opposite directions, of series of parts movable into and out of position to limit movement of said elements in one direction, an actuator for each series of said 40 parts, and means for operating said actuators to move said parts to position to limit movement of said reciprocating elements.

20. In an adding machine, the combination 45 with a series of reciprocating elements, and mechanism for operating said reciprocating elements in opposite directions, of series of parts movable into and out of position to limit movement of said reciprocating elements in one direction, an actuator for moving said parts into and out of position to limit movement of said elements, mechanism for operating said actuators to 50 move said parts into position to limit movement of said elements, and means holding said parts in position to be engaged by said elements and for guiding said elements into engagement with said parts.

21. In an adding machine, the combination 60 with a series of reciprocating elements, and means for actuating said reciprocating elements in opposite directions, of series of parts movable into and out of position to limit movement of said elements in one direction, an actuator for each series of parts,

mechanism for selecting the parts to be actuated and for operating said actuators to move said parts to position to limit movement of said elements, means for holding said parts in position to be engaged by said 70 elements and for guiding said elements into engagement with said parts, and mechanism for operating said actuators to move said parts out of position to limit movement of said elements.

22. In an adding machine, the combination 75 with a series of reciprocating elements, and means for actuating said reciprocating elements in opposite directions, of series of parts movable into and out of position to limit movement of said elements in one direction, and actuator for each series of parts, mechanism for selecting the parts to be actuated and for operating said actuators to move said parts to position to limit 80 movement of said elements, means for holding said parts in position to be engaged by said elements and for guiding said elements into engagement with said parts, and automatic mechanism for operating said actuators to move said parts out of position to limit movement of said elements.

23. In an adding machine, the combination 85 with a series of reciprocating elements, and means for actuating said reciprocating elements in opposite directions, of series of parts movable into and out of position to limit movement of said elements in one direction, an actuator for each series of parts, mechanism for selecting the parts to be 90 actuated and for operating said actuators to move said parts to position to limit movement of said elements, means for holding said parts in position to be engaged by said elements and for guiding said elements into 95 engagement with said parts, and manually operable mechanism for operating said actuators to move said parts out of position to limit movement of said elements.

24. In an adding machine, series of stops, 100 a positioning device for each series of stops, an escapement, and keys for operating said escapement to cause said positioning device to position said stops.

25. In an adding machine, series of laterally 115 movable stops, means for moving laterally certain of said stops while the remaining stops remain in idle position, and mechanism for operating said means to restore said stops to idle position.

26. In an adding machine, series of laterally 120 movable stops, actuators for moving laterally any desired ones of said stops while the remaining stops remain in idle position, and keys each controlling all of said actuators.

27. In an adding machine, the combination 125 with series of movable parts adapted to be positioned to represent numbers, of guides in which the respective series of parts are 130

movable to position to represent numbers and a rotary positioning device operable to move each series of parts to position to represent numbers.

5 28. In an adding machine, the combination with series of movable parts adapted to be positioned to represent numbers, of a rotary positioning device operable to move each series of parts successively to position 10 to represent numbers, and optional means for bringing said parts selectively under control of said positioning devices.

15 29. In an adding machine, the combination with series of parts movable to and from position to represent numbers, of a rotary positioning device for each series of parts, mechanism for selectively bringing said parts under control of said positioning devices, and mechanism for operating said 20 positioning devices concurrently whereby the selected parts will be maintained in proper relative positions.

25 30. In an adding machine, the combination with series of parts movable to and from position to represent numbers, of an actuator for each series of parts, means for selectively bringing said parts under control of said actuators, means for operating said actuators, and guides in which said parts are 30 movable.

35 31. In an adding machine, the combination with series of parts adapted to be positioned to represent numbers, a rotary positioning device for each of said series of parts, mechanism for selectively bringing said parts under control of said positioning devices, mechanism for operating said positioning devices to position the selected parts to represent numbers, and automatic means 40 for operating said positioning devices to restore said parts to their starting points.

45 32. In an adding machine, the combination with parts adapted to be positioned to represent numbers, of a rotary actuator for each series of parts, mechanism for selectively bringing said parts under control of said actuators, mechanism for operating said actuators concurrently to position said parts to represent numbers, and manipulative 50 means for operating said actuators to restore said parts to their starting points.

55 33. In an adding machine, the combination with a series of stationary supports, and a series of parts supported by each of said stationary supports and adapted to be moved therefrom to positions to represent numbers, of mechanism for selectively moving said parts from said supports to positions to represent numbers, and manipulative means for actuating a part of said mechanism to move said parts to their starting points upon said supports.

60 34. In an adding machine the combination with a series of stationary supports, and a series of parts on each of said supports

adapted to be moved therefrom to positions to represent numbers, of mechanism for selectively moving said parts from said supports, actuators for moving said selected parts to positions to represent numbers, 70 means for concurrently operating said actuators to move said parts to positions to represent numbers, and automatic mechanism for operating said actuators to move said parts to their starting points upon said supports. 75

35. In an adding machine, a series of adding wheels, racks for operating said adding wheels, movable projections carried by said racks, stops engaged by said projections to prevent operation of said racks, a revolute support for holding and moving said stops, means for rotating said support to disengage said stops from said projections in adding operations, and means for disengaging said projections from said stops, to permit operation of said racks, and adding wheels in clearing operations, substantially as specified.

36. In an adding machine, stops, positioning devices operable to position said stops to represent numbers, elements holding said stops off of said positioning devices, keys, and mechanism for operating said elements and said positioning devices to release and position one stop at each operation of any one of said keys.

37. In an adding machine, a series of magazines, a plurality of stops in each magazine, means holding said stops in said magazines, means for releasing said stops one at 100 a time from said magazines, respectively, means for positioning said stops to represent numbers, and devices for actuating said positioning means to return said stops into said magazines.

105 38. In an adding machine, differential mechanism comprising a series of stops for each of several digits, an actuator for positioning selectively all of the stops of each series, escapement mechanism for operating 110 said actuators, and keys controlling said escapement mechanism.

39. In an adding machine, differential mechanism comprising an element corresponding to each of several digits, stops controlled by said elements, and means for operating said elements to position said stops selectively to represent numbers.

115 40. In an adding machine, differential mechanism comprising stops adapted to be 120 positioned to represent numbers, means for holding said stops, keys for operating said holding means to release one stop at each operation of certain of said keys, revolute devices for actuating said stops and positioning said stops to represent numbers incidentally to the release of said stops as aforesaid, means for operating said revolute devices, and guides preventing displacement of said stops.

41. In an adding machine, a magazine, a plurality of stops in said magazine, an abutment holding said stops in said magazine, means for controlling said abutment to release said stops one at a time from said magazine while said magazine remains stationary, an actuator for positioning said stops to represent numbers and means for operating said actuator to return said stops into said magazine.

42. In an adding machine, differential mechanism comprising an element corresponding to each of several digits, a series of stops controlled by each of said elements, means for operating said elements to position said stops selectively to represent numbers, and guides holding said stops in engagement with said operating means.

43. In an adding machine, differential mechanism comprising a series of elements corresponding respectively to each of several digits, a series of parts adapted to be positioned to represent numbers, means for selectively bringing said parts under control of said elements, and mechanism for operating said elements effectively to position said selected parts to represent numbers.

44. In an adding machine, differential mechanism comprising a series of elements corresponding respectively to each of several digits, a series of parts adapted to be positioned to represent numbers, selecting means and coöperating actuating means for selectively bringing said parts under control of said elements and actuating said elements effectively to position the selected parts to represent numbers, and means preventing displacement of said parts with respect to said elements.

45. In an adding machine, differential mechanism comprising a series of elements corresponding respectively to each of several digits, a series of parts controlled by each of said elements and adapted to be positioned to represent numbers, means for selectively bringing said parts under control of said elements, mechanism controlled by said last-named elements effectively to position the selected parts to represent numbers, and manual means for actuating said elements to restore said parts to their starting points.

46. In an adding machine, the combination of elements corresponding respectively

to each of several digits, a series of parts adapted to be positioned to represent numbers, mechanism for operating said elements to position selected parts to represent numbers, automatic mechanism for actuating said elements to restore said parts to their starting points, and optionally operable means for actuating said elements to restore said parts to their starting points.

47. In an adding machine, a series of elements corresponding respectively to each of several digits, a series of parts adapted to be positioned to represent numbers, mechanism for selectively bringing said parts under control of said elements to position said parts to represent numbers, a rock shaft, automatic means controlled by said rock shaft for actuating said elements to restore said parts to their starting points, and optional means for preventing said automatic means from actuating said elements.

48. In an adding machine, a magazine, a plurality of elements in said magazine, mechanism for selecting and positioning said elements to represent numbers, means for returning said elements into said magazine, and repeating mechanism adjustable to prevent said elements from being returned into said magazine.

49. In an adding machine, a magazine, a plurality of elements in said magazine, means for moving said elements successively to different numerical orders, and manipulative means for restoring said elements into said magazine.

50. In an adding machine, elements settable to represent numbers, revolute members for setting said elements successively to represent said numbers, and a key controlling said revolute members.

51. In an adding machine, a series of elements settable to represent the digits of numbers, a revolute member for setting said elements to represent the digits of numbers, mechanism for actuating said revolute member, and a key controlling said mechanism.

In witness whereof, I have signed this specification in the presence of two subscribing witnesses.

HARRY LANDSIEDEL.
